ATTORNEY

UNITED STATES PATENT OFFICE.

WILLIAM W. SPURRIER, OF ST. LOUIS, MISSOURI, ASSIGNOR OF THIRTY-EIGHT PER CENT TO BEN F. SCHUETZ, OF JEFFERSON CITY, MISSOURI.

BURGLARPROOF CONTAINER.

Application filed June 30, 1922. Serial No. 571,987.

To all whom it may concern:

Be it known that I, WILLIAM W. SPURRIER, a citizen of the United States, residing in St. Louis County, State of Missouri, have 5 invented a certain new and useful Improvement in Burglarproof Containers, of which the following is a specification, reference being had to the accompanying drawings, forming a part thereof.

10 This invention relates generally to containers and, more particularly, to a certain new and useful improvement in what I have designated as containers of so-called burglar-proof type, the principal object of my 15 present invention being to provide a grip, satchel, or other such container with means including a missile-projector or small arm, such as a pistol or revolver, disposed within the container and readily and easily fired 20 or discharged by the carrier of the grip for the purpose, on an attempt to obtain unauthorized possession of the container, either of giving an alarm or of injuring the one who may so endeavor or attempt to obtain 25 possession of the grip against the will of the carrier.

With the above and other objects in view, my present invention resides in the novel 30 features of form, construction, arrangement, and combination of parts hereinafter described and afterwards pointed out in the claims:

In the accompanying drawings:

35 Figure 1 is a side elevational view of a container in the form of a grip or satchel equipped with an alarm or missile-projecting means embodying my invention;

Figure 2 is an enlarged fragmental view 40 of the grip;

Figure 3 is an end view of the grip; and

45 Figures 4 and 5 are enlarged fragmental views of the grip, showing some of the spring gripping members or fingers of the small arm or pistol included in my invention.

Referring now more in detail and by reference characters to the said drawings, which illustrate a practical embodiment of my invention, I have shown my invention in 50 connection with a container in the form of a grip or satchel A having a body comprising a bottom wall 1, side walls 2-2, and end walls 3-3, the latter being upwardly elongated or extended, as at 4-4, to pro-

ject above the plane of the upper edges of 55 the side walls 2-2. The end extensions 4-4 are for the most part oppositely beveled or cut-away at their side edges, as at 5-5 for cooperation with oppositely swingable top-wall sections 6-6 hinged at 60 a side edge, as at 7, to the upper edges of the side walls 2-2, the cover or top sections 6-6 being formed or provided at their other or free side edge with forwardly presented flanges 8-8 adapted to partly overlap when such sections are in closed position and at their end edges with laterally presented flanges 8'-8' adapted to overlap the beveled upper edges of the end wall extensions 4-4 also when the cover or top-sections are in closed position. Suitably attached to the top sections 6-6, are handle members 9-9, the cover or top sections being releasably locked in closed position as by any suitable means, such, for instance, 75 as registering eyes 10-10 disposed upon the top-sections 6-6 and an engaging or locking hasp 11.

Riveted to or otherwise fixed flatwise upon the inner face of one of the cover-sections 6, is a preferably metallic plate 12, and suitably located in spaced relation upon the plate 12, is a plurality of complementing or co-operating pairs of preferably yielding or spring members or fingers 13 80 adapted to grip and thereby efficiently support upon the plate 12 and within the grip a suitable small fire-arm or missile-projector preferably in the form of a revolver or pistol 14. Preferably the several pairs 90 of gripping fingers 13 are relatively adjustable, as by means of slot and pin connections 15 with the plate 12, to readily accommodate and support revolvers or pistols of different types or sizes. 95

Suitably pivoted, as at 16, upon plate 12 for rocking movement relatively to the fire-arm 14, is what might well be designated a substantially S-shaped lever 17 formed or provided at one end with a laterally projecting finger 18 adapted for actuating or tripping engagement with the trigger 19 of the fire-arm 14. At its other end, the lever 17 is formed preferably integrally with a relatively obliquely disposed extension or 100 arm 20 provided at its free end with a transversely or laterally disposed pin or stud 21 disposed for movement in a suitably 105

arcuated slot 22 formed in the grip or container top-section 6, as best seen in Figures 1 and 2. Suitably attached to pin or stud 21 and of a length to extend within convenient reach of one grasping the grip-handles 9—9, is an apertured finger-grip 23 of stiff leather or other suitable material, an end-wall extension 4 of the grip A being preferably cut-away and thereby apertured, 10 as at 24, in alignment with the barrel 25 of the revolver 14.

The revolver or pistol 14 may be of any suitable preferably repeater type, and in use or operation, it will now readily be evident 15 that the person carrying the grip by means of its handles 9—9 may by means of the finger-grip 23, in the event of a "hold-up" or attempt by an unauthorized person to obtain possession of the grip, quickly rock- 20 ingly actuate the lever 17 and thereby discharge the revolver or pistol 14, such action being repeated as may be required and the discharges of the fire-arm either sounding an alarm or, should, as would be natural, 25 the grip as a whole and consequently the revolver 14 be so held that the barrel 25 of the revolver were pointed at the person making the attempt to obtain possession of the bag, resulting in bodily injury to him. Due to 30 the peculiar shape or form of the trigger-actuating lever 17, there is permitted a relatively large amount of play between the trigger 19 and the lever 17 to accommodate accidental movements of the finger-grip 23, 35 the actual tripping of the trigger 19 being accomplished in the final movement or travel of pin 21 towards the upper end of slot 22.

As an additional safe-guard against unauthorized appropriation of the grip A, I 40 preferably, as by a pair of grippers 26, removably support an obnoxiously or offensively odorous bomb 27 within the body of the grip A and across the bullet or missile aperture 24, which bomb will be exploded 45 on the first discharge of the revolver 14 and make it practically impossible for anyone, even the rightful owner or carrier of the grip A, to again carry or open the grip until the offensive odor released on explosion 50 of the bomb 27 has entirely disappeared.

I may add that the grip A is preferably entirely of steel, exteriorly covered, and aperture 24 concealed, by leather or other suitable material, the grip or container being especially useful by bank-messengers 55 and the like for the transportation of money, securities, or the like; and it is to be understood that changes in the form, construction, arrangement, and combination of the 60 several parts of my new container may be made and substituted for those herein shown and described without departing

from the nature and principle of my invention.

Having thus described my invention, 65 what I claim and desire to secure by Letters Patent is:

1. The combination with a slotted container having a handle, of a fire-arm disposed within the container, and means for 70 discharging the fire-arm, said means including a lever mounted for rocking movement within the container and having tripping engagement with the trigger of the fire-arm, the lever having a portion disposed at 75 the slot of the container, and a member having engagement through said slot with the lever for rocking the same, said member being disposed for gripping exteriorly of the container and adjacent the handle. 80

2. The combination with a slotted container, of a fire-arm disposed within the container, and means for discharging the fire-arm, said means including a lever mounted 85 for rocking movement within the container and having tripping-engagement with the trigger of the fire-arm, an extension on the lever movable in the slot of the container, and a gripping-member disposed exteriorly of the container and having engagement 90 with the lever-extension for actuating the lever.

3. The combination with a slotted container, of a fire-arm disposed within the container, and means for discharging the fire- 95 arm, said means including a substantially S-shaped lever pivoted intermediate its ends for rocking movement within the container, an extension on one end of the lever having tripping engagement with the trigger of the 100 fire-arm, an extension on the other end of the lever projecting for movement in the slot of the container, and a gripping-member disposed exteriorly of the container and having engagement with the second 105 lever-extension for actuating the lever.

4. The combination with a slotted container and an explosive bomb located within the container, of a fire-arm supported within the container, the barrel of the fire-arm being disposed in the direction of the bomb, and means for discharging the fire-arm for exploding the bomb, said means including a lever mounted for rocking movement 110 within the container and having tripping engagement with the trigger of the fire-arm, the lever having a portion disposed at the slot of the container, and a member disposed for gripping exteriorly of the container having engagement through said slot with the lever for rocking the same. 115

In testimony whereof, I have signed my name to this specification.

WILLIAM W. SPURRIER.
